FIG. 5.

FIG. 6.

INVENTOR.
JOSEPH C. FULKERSON,
BY

M^o Morrow, German & Davidson
ATTORNEYS.

An extension 56 from the adjacent end of the lower frame center member 12 is disposed at one end below the guides 42 and 44.

A sleeve 46 is disposed between the two guides 42 and 44 and has upper and lower annular flanges 50 thereon which contact the upper and lower edges of the guides to maintain the sleeve in the guideway. An extension 52 depends from the sleeve below the lower flange 50 and is secured at its upper end to the outer end of the extension 56 of the lower frame center member 12.

The sleeve extension 52 has in one side an elongated slot 54 extending from adjacent the lower sleeve flange 50 to the lower end of the extension and a vertical strut 58 is slidably mounted in the sleeve 46 and its depending extension 52. A wheel 61 is journaled on an angularly-disposed arbor 69 at the lower end of this strut to support the strut on the ground and the sleeve 46 is movable longitudinally of the strut, by a hand lever 60, to raise and lower the adjacent ends of the upper and lower frames. This hand lever is pivotally connected intermediate its length to the sleeve extension 52 by a pivot pin 62. A pin 55 secured at one end to the strut 58 projects through slot 54 in the sleeve extension and is received at its opposite end in an elongated aperture 67 in the hand lever 60 at a location spaced from pivot pin 62 so that movement of the lever about the pivot pin will raise and lower the sleeve 46 relative to the strut 58.

A toothed quadrant 63 is carried by the sleeve extension 52 and a detent, not illustrated, carried by the lever 60, engages the teeth of the quadrant to releasably lock the lever in adjusted position.

The draft beam 36 extends from the shaft 34 beyond the guide members, and somewhat beyond the outer guide member 44 is bent downward and then outward so that the downwardly-bent portion will clear the wheel 61, and the outwardly-bent portion is at the proper level for attachment to draft means, such as a farm tractor.

A link 68 is pivotally connected at one end to the outwardly-bent portion of the draft beam adjacent the downwardly-bent portion of the latter and is pivotally connected at its opposite end to the adjacent end of a second link 66, the opposite end of which is secured to a sleeve 65 journaled on the strut 58 below the sleeve extension 52.

Two vertically-disposed sleeves 70 and 72 are secured to the end member 26 of the upper frame near the respectively-opposite ends of such end member, and vertically-disposed struts 76 and 78 are slidably received in the sleeves 70 and 72, respectively.

Each of these struts has, at its lower end, an angularly-disposed arbor, a indicated at 82, and wheels, as indicated at 84, are journaled on these arbors respectively to support the associated struts on the ground.

The struts 76 and 78 extend upwardly through the sleeves 70 and 72, respectively, and a toothed quadrant 88 is secured to each strut above the corresponding sleeve. A hand lever 90 is pivotally connected intermediate its length to each strut 76 and 78 above the associated sleeve and below the upper end of the strut. Links 94 are pivotally secured at their upper ends respectively to the levers 90 at corresponding ends of the levers, and these links are pivotally connected at their lower ends to the end member 26 of the upper frame, so that the sleeves 70 and 72 can be moved by the

levers longitudinally of the struts 76 and 78 to raise and lower the corresponding ends of the upper and lower frames. Suitable detents, not illustrated, are provided on the levers 90 to engage the teeth of the quadrants 88 and releasably secure the levers in adjusted positions.

Each of the sleeves 70 and 72 has in one side an elongated slot 74 opening to the lower end of the sleeve, and a pin 80 is secured at one end to each strut and projects through the corresponding slot 74, these pins serving to restrain the struts against rotation relative to the associated sleeves.

It will be noted that the pin 55 serves to restrain the strut 58 against rotation relative to the sleeve 46 as well as to provide a connection between the hand lever 60 and strut 58. The sleeve 46 is held against rotation or other movement relative to the center member of the lower frame, but its angular relationship to the center member of the upper frame will change slightly as the sleeve moves from one end of the guideway to the other.

The manner of reversing the plow is clearly illustrated in Figures 1, 5 and 6.

In Figure 1, the draft beam 36 extends downwardly, indicating the corresponding direction of movement of the plow. It will be noted that the two wheels 84 are at the left, and the single wheel 61 at the right. When the plow reaches the end of the furrow, the plow-pulling team or tractor is turned sharply around the single wheel end of the plow. Draft beam 36 swings about its pivotal connection with the upper and lower frames and links 66 and 68 buckle, permitting beam 36 to swing over sleeve 46. During this swinging movement of the draft beam from one side of the machine to the other, the connecting link 66 may first swing inwardly about the strut 58 until the link 68 comes into contact with the sleeve 65. Link 68 will then force the strut and sleeve 46 to that end of the guideway between guides 42 and 44 toward which the draft beam is swinging. Link 68 will then turn link 66 outwardly about the strut, the links clearing the wheel 61, the lower frame and the discs 2. After the draft beam passes the sleeve 46, the links 66 and 68 straighten out and the plow is reversed and ready for operation in the corresponding direction, as indicated by the upwardly-extending direction of the draft beam in Figure 6.

The angular relationship between draft beam 36 and lower frame 10 carrying discs 2, is exactly the same in both Figures 1 and 6, so that the plow operates in the same manner in both directions of travel, always turning the furrows in the same direction and plowing the land level with no corners or ridges, so that the land can be easily irrigated and the need for harrowing is greatly minimized.

Although I have described a preferred embodiment of my invention in specific terms, it is to be understood that various changes may be made in size, shape, materials and arrangement without departing from the spirit and scope of the invention as claimed.

I claim:

1. A disc type reversible plow comprising a rectangular lower frame, a shaft extending longitudinally of said lower frame and rotatably supported thereby, a plurality of discs secured on said shaft in spaced-apart, substantially co-axial relationship, an upper frame overlying said lower frame, means pivotally inter-connecting said upper and lower frames, a pair of spaced-apart

struts secured to one end of said upper frame, ground-engaging wheels journaled respectively on said struts for supporting the adjacent ends of both of said frames, an arcuate guideway at the opposite end of said upper frame, a sleeve slidable in said guideway longitudinally thereof, a third strut extending through said sleeve, a ground-engaging wheel journaled on said third strut for supporting the adjacent ends of said upper and lower frames, means connecting said sleeve to the adjacent end of said lower frame to constrain said lower frame to turn relative to said upper frame about the pivotal connection between said frames when said sleeve moves in said guideway, a draft beam pivotally connected to said upper frame at a location spaced from said guideway for swinging movement from one side of said plow to the other whenever the direction of travel of said plow is reversed, and means connecting said draft beam to said sleeve to move said sleeve along said guideway from one operative position to its alternative operative position when said draft beam is swung from one to the opposite side of the plow to thereby maintain the proper angular relationship between said upper and lower frames for both directions of travel of the plow.

2. A disc-type plow comprising a lower rectangular frame, a shaft journaled at its ends in bearings secured to said frame, a plurality of discs secured in spaced-apart axially aligned relation on said shaft, an upper rectangular frame overlying said lower frame, means pivotally connecting said frames adjacent their centers, a guide ring on said lower frame centered on the axis of said frame-connecting means, a complementary guide ring on said upper frame, a pair of sleeves secured to one end of said upper frame, one adjacent each side of the latter, a respective strut in each sleeve, each strut hav-

ing a bent lower end, a respective wheel journaled on the lower end of each strut, an arcuate guideway at the opposite end of said upper frame, a sleeve slidable in said guideway, means rigidly connecting said slidable sleeve to said lower frame, a third strut extending through said sleeve and having a bent lower end, a third wheel journaled on the lower end of said third strut, a draft beam pivotally secured adjacent one end thereof to said upper frame and shiftable between alternative operative positions of either side of said frame, and a pair of pivotally joined links extending between said third strut and said draft beam intermediate the length of the latter to move said slidable sleeve through said guideway when said draft beam is shifted from one side to the other of said upper frame to maintain substantially the same angular relationship between said draft beam and said lower frame for both operative positions of said draft beam relative to said upper frame.

JOSEPH C. FULKERSON.
